CARMINE BILOTT, OF LARIMER, PENNSYLVANIA.

DESIGN FOR A BURIAL-CASKET CONTAINER.

55,407.

Specification for Design.

Patented June 8, 1920.

Application filed October 23, 1919. Serial No. 332,836. Term of patent 14 years.

To all whom it may concern:

Be it known that I, CARMINE BILOTT, a citizen of the United States, and a resident of Larimer, in the county of Westmoreland and State of Pennsylvania, have invented a new, original, and ornamental Design for Burial-Casket Containers, of which the following is a specification, reference being had to the accompanying drawings, forming a part thereof:

Figure 1 is a plan view; Fig. 2 is a side elevation and Fig. 3 is an end elevation.

My design is characterized by the tapered plane surfaces which converge toward each other from one end of the container to the other and the appearance shown in Fig. 3 is that presented to an observer looking toward the smaller end of the container.

I claim:—

The ornamental design for a burial casket container, substantially as shown.

CARMINE BILOTT.
